UNITED STATES PATENT OFFICE.

FRANK D. KELLY, OF RICH VALLEY, MINNESOTA.

ROTARY ENGINE.

No. 926,743.

Specification of Letters Patent.

Patented July 6, 1909.

Application filed April 19, 1909. Serial No. 490,897.

To all whom it may concern:

Be it known that I, FRANK D. KELLY, a citizen of the United States, residing at Rich Valley, in the county of Dakota and State of Minnesota, have invented certain new and useful Improvements in Rotary Engines; and I do hereby declare the following to be a full, clear, and exact description of the invention, such as will enable others skilled in the art to which it appertains to make and use the same.

My invention has for its object to provide an improved rotary engine, and to this end it consists of the novel devices and combinations of devices hereinafter described and defined in the claims.

In the accompanying drawings, which illustrate the invention, like characters indicate like parts throughout the several views. Referring to the drawings, Figure 1 is a transverse vertical section taken on the line $x^1 x^1$ of Fig. 2; and Fig. 2 is a longitudinal vertical section taken on the line $x^2 x^2$ of Fig. 1.

The cylinder casting or casing 1 is provided with an internal cylindrical piston seat 2, the diameter of which, at its outer ends, is increased so as to form annular stop shoulders 3. The opening through the casing 1 formed by the piston seat 2 is closed at each end by a detachable cylinder head 4, which is secured to the casing 1 by machine screws 5. A rectangular steam chest 6 is also formed in the upper portion of the casing 1 above the cylinder seat 2 and is provided with a detachable cover 7 secured to the casing 1 by machine screws 8 and forms a steam tight joint therewith.

Steam is supplied to the steam chest 6 from a suitable boiler, not shown, through a valve-equipped steam pipe 9. An inverted cup-shaped reversing valve 10 works over the bottom of the steam chest 6 and is provided with a valve stem 11 which works through a stuffing box 12 in the left hand side of the steam chest 6 with respect to Fig. 2. The outwardly projecting end of the valve stem 11 is pivotally connected at 13 to an operating lever 14, which lever is pivotally secured, at its lower end, to a bracket 15 secured to the base of the casting 1.

A pair of parallel and laterally spaced ports 16 and 17 are formed in the casing 1 and extend approximately tangentially from

opposite sides of the piston seat 2 (see Fig. 1) and open into the steam chest 6 on opposite sides thereof. An exhaust port 18 is also formed in the casing 1 between the steam chest 6 and piston seat 2 and opens into the steam chest 6 under the reversing valve 10 and midway between the two ports 16 and 17.

An exhaust pipe 19 is screw-threaded into the outer end of the exhaust port 18 and forms an extension thereof. A rotary piston is mounted in the piston seat 2 between the shoulders 3 and comprises a pair of laterally spaced heads 20 and intermediate propeller blades 21. The propeller blades 21 are cast integrally with a hub 22 and project radially therefrom at right angles to each other. The heads 20 are rigidly secured to the hub 22 and closely engage the ends of the propeller blades 21 and form steam tight joints therewith. At their free edges, the propeller blades 21 are grooved to receive spring pressed packing strips 23. These packing strips 23 engage the cylindrical surface of the seat 2 and make steam tight joints with the surfaces they engage. A pair of supplemental piston heads 24, of larger diameter than the heads 20, are loosely mounted one on each end of the hub 22, outside of the heads 20, and spaced apart therefrom a sufficient distance to permit the supplemental heads 24 to bear against the shoulders 3 and form steam tight joints therewith. The supplemental heads 24 are adjustably and detachably secured to the piston heads 20 by a pair of long nutted bolts 25 passed through the heads 20 and 24. By adjusting the nuts on the bolts 25, it is evident that the supplemental heads 24 may be made to bear more or less against the shoulders 3. The supplemental heads 24 also hold the rotary piston in working position and prevent endwise movement thereof. A power transmission shaft 26 works through a stuffing box 27 in the right hand cylinder 24 with respect to Fig. 2, and its inner end is rigidly secured to the adjacent end of the hub 22.

When the reversing valve 10 is in the position as indicated in Fig. 1, steam will be blown through the port 16 and against the propeller blades 21 and the rotary piston rotated in the direction of the arrow marked on Fig. 1. When the reversing valve 10 is moved into a position reverse from that

shown in Fig. 1, the rotary piston will be rotated in a direction reverse from that indicated by the arrow marked on Fig. 1.

What I claim is:

- 5 1. In a rotary engine, the combination with a casing having a piston seat, the ends of which are formed with stop shoulders, an admission port and an exhaust port, of a rotary piston mounted in said seat and comprising a pair of laterally spaced heads and intermediate propeller blades, and a pair of supplemental piston heads secured one to each end of said piston for coöperation with said stop shoulders, substantially as described.
- 10 2. In a rotary engine, the combination with a casing having a piston seat, the ends of which are formed with stop shoulders, an admission port and an exhaust port, of a rotary piston mounted in said seat and comprising a pair of laterally spaced heads and intermediate propeller blades, and a pair of supplemental piston heads secured one to each end of said piston for coöperation with said stop shoulders and at least one of said supplemental heads being adjustable with respect to said piston, substantially as described.
- 15 3. In a rotary engine, the combination with a casing having a piston seat, an admission port, an exhaust port and a detachable head, the ends of said piston seat being enlarged to form annular stop shoulders, of a rotary piston mounted in said seat and comprising a pair of laterally spaced heads and intermediate propeller blades, a shaft mounted in said casing and secured to said rotary piston, and a pair of supplemental

piston heads adjustably secured to said rotary piston for coöperation with said stop shoulders, substantially as described.

4. In a rotary engine, the combination with a casing having a piston seat, an admission port, an exhaust port and a detachable head, the ends of said piston seat being enlarged to form annular stop shoulders, of a rotary piston mounted in said seat and comprising a pair of laterally spaced heads and intermediate propeller blades, spring-pressed packing strips mounted in the edges of said propeller blades, a shaft mounted in said casing and secured to said rotary piston, and a pair of supplemental piston heads adjustably secured to said rotary piston for coöperation with said stop shoulders, substantially as described.

5. In a rotary engine, the combination with a casing having a steam chest, a piston seat, the ends of which are formed with stop shoulders, an admission port and an exhaust port connecting said steam chest and said piston seat, and a reversing valve mounted in said steam chest, of a rotary piston mounted in said seat and comprising a pair of laterally spaced heads and intermediate propeller blades, and a pair of supplemental piston heads secured one to each end of said piston for coöperation with said stop shoulders, substantially as described.

In testimony whereof I affix my signature in presence of two witnesses.

FRANK D. KELLY.
